UNITED STATES PATENT OFFICE.

JOHN SCHIES, OF ANDERSON, INDIANA.

DESIGN FOR A JAR-FASTENING BAR.

SPECIFICATION forming part of Design No. 28,026, dated December 14, 1897.

Application filed October 25, 1897. Serial No. 656,372. Term of patent 14 years.

To all whom it may concern:

Be it known that I, JOHN SCHIES, residing at Anderson, in the county of Madison and State of Indiana, have invented and produced a new 5 and original Design for Die-Formed Jar-Fastening Bars, of which the following is a specification, reference being had to the accompanying drawings, forming part thereof, in which—

10 Figure 1 is a top plan view of my fastening-bar. Fig. 2 is a side view thereof; and Fig. 3 is a perspective view of the bar, showing my new design.

15 The leading or material feature of my design consists of the longitudinal sections A and the cross-section B, such sections A being arranged out of alinement and on parallel lines and the section B being extended at right angles to the sections A and united 20 thereto by curved sections C, such sections C by their juncture with the sections A simulating the appearance of the line of beauty, the parts A, B, and C lying in the same plane, as will be understood from Figs. 2 and 3.

At the outer ends of the sections A, I provide the short sections D, which incline inwardly and are formed on straight lines from their juncture with the sections A to their extremities, the said sections D being in approximately the same plane and on similar 25 angles, so that such sections, if extended, will intersect at a point dropped from a point midway between the ends of the sections A.

Having described my invention, what I claim as new, and desire to secure by Letters 35 Patent, is—

The design for a jar-fastening bar, as herein shown and described.

JOHN SCHIES.
